UNITED STATES PATENT OFFICE.

FREDERICK K. LORD, OF BAYONNE, NEW JERSEY.

SPLINE-WEIGHT.

SPECIFICATION forming part of Letters Patent No. 764,482, dated July 5, 1904.

Application filed February 18, 1904. Serial No. 194,135. (No model.)

To all whom it may concern:

Be it known that I, FREDERICK K. LORD, a citizen of the United States, and a resident of Bayonne, in the county of Hudson and State 5 of New Jersey, have invented a new and Improved Spline-Weight, of which the following is a full, clear, and exact description.

The invention relates to drawing instruments; and its object is to provide a new and 10 improved spline-weight arranged to firmly hold the spline or batten in a curved position at any desired place on the drawing-surface to allow the draftsman to conveniently draw a line along the unobstructed front edge of 15 the spline.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a plan view of the improvement. Fig. 2 is a sectional side elevation of the same on the line 2 2 of Fig. 1, and Fig. 3 is a cross-section of the same on the line 3 3 of Fig. 1.

30 The body A of the spline-weight is preferably made of metal and provided at one end with a handle A', adapted to be taken hold of by the draftsman for conveniently moving the body over the drawing B to the desired place. The under side or bottom of the body A is preferably covered with a fabric A² to hold the body A against accidental sliding on the surface of the drawing-paper and also to protect the drawing from being scratched by 35 the weight, it being understood that the body is made solid and sufficiently heavy to firmly rest on the surface of the drawing-paper to allow drawing the desired line without requiring other fastening means for holding the body to the surface of the paper.

40 On the front portion of the body A is secured a transversely-extending bar C, in which screw a number of clamping-screws D, each extending with its shank through an 45 elongated slot E', formed lengthwise in a fin-

ger E, having a downwardly-curved point E², adapted to engage the top surface of a spline or batten F, preferably made of soft rubber and having a front face F', of hardened rubber, along which front face the line is drawn 55 by a suitable drawing-tool upon the surface of the drawing-paper. By loosening the clamping-screws D the fingers E can be adjusted lengthwise or turned on the clamping-screws to bring the points of the fingers into 60 the desired position to give the desired curvature to the spline and to hold the same firmly down on the drawing-paper B, so that the front edge F' of the spline conforms to the shape 65 of the line to be drawn and the spline is held firmly in place to allow the draftsman to draw a line along the edge F' upon the drawing-paper. As the body A is held against accidental movement on the drawing-paper, it is 70 evident that the spline F is similarly held, and the draftsman is enabled to accurately draw the desired line along the edge F' upon the drawing-paper. By the arrangement described the line may be duplicated on another portion of the drawing-paper by the operator 75 sliding the body A, and with it the spline F, on the drawing-paper until the desired place is reached, it being understood that the points E² of the fingers embed themselves sufficiently 80 in the soft material of the spline to move the latter along on shifting the body A, as above explained.

The top surface of the cross-bar C is preferably a distance above the top surface of the body A, so as to allow convenient adjusting 85 of the fingers E for the points thereof to properly engage the top surface of the flexible spline F, the points of the fingers leaving the front edge F' of the spline completely unobstructed to enable the draftsman to conveniently draw the line along the said edge.

The device described is especially serviceable in laying out lines for marine vessels and the like.

Having thus described my invention, I claim 95 as new and desire to secure by Letters Patent—

1. A spline-weight comprising a heavy body adapted to rest on a drawing, and a plurality of fingers held adjustably on the said body and provided with points for engaging the 100

top of the flexible spline, to hold the latter down in firm contact with the surface of the drawing, and leaving the front edge of the spline unobstructed, as set forth.

5 2. The combination with a flexible spline, of a spline-weight having a heavy rigid body, provided on its bottom with means for holding the weight against accidental sliding on the surface of a drawing, and fingers adjust-
10 ably secured on the body and adapted to frictionally engage the top of the said spline, to hold the latter firmly down on the surface of the drawing, as set forth.

15 3. A spline-weight having a rigid heavy body provided at one end with a handle, and

at the other end with a transverse bar, extending with its top surface above the top surface of the said body, clamping-screws screwing in the said bar, and fingers having elongated slots, through which extend the said clamp-
20 ing-screws, the fingers having downwardly curved points for frictionally engaging the top surface of a flexible spline, as set forth.

In testimony whereof I have signed my name to this specification in the presence of two sub-
25 scribing witnesses.

FREDERICK K. LORD.
